GRILLE

John Karmazin, Grosse Ile, Mich., assignor to
Karmazin Engineering Company, a corporation
of Michigan

Application November 13, 1933, Serial No. 697,756

9 Claims. (Cl. 189—82)

This invention relates to an improved grille for ventilation, ornamentation, air conditioning and other purposes and to a method of producing the same.

In previous grilles for ventilation and other purposes it has been the practice to provide a plurality of horizontal members and of transverse members with air passages between the members so as to provide for the passage of air into or out of the space to be ventilated. In some instances these grilles have been stamped out of one piece of metal in rectangular or diamond shape. In other instances they have been formed by rods extending through fin elements providing a more symmetrical type of grille and one of more substantial construction which will permit uniform flow of air therethrough without whistling or other objectionable sounds. In producing grilles of the former type, a separate die, often of large size, is necessary for each size and shape produced and in the latter type, special jigs and fixtures are necessary for each size, making the outlay for tools and dies unusually expensive, thereby increasing the cost of production and limiting the number of sizes and shapes which can be produced.

One of the objects of my invention is to produce a desirable grille of the fin type which can be made by drawing tubular projections from sheets of strip material and then nesting the tubular projections of one strip member into the tubular projections of another strip member to form a grille which is of regular contour and at the same time cheap to construct as one set of dies can be used, to produce innumerable sizes by merely changing the length of the strips or the number of strips nested together.

Another object of the invention is to provide a grille and method of producing the same whereby the shape of the individual elements and therefore of the entire grille may be readily changed to secure different ornamental effects, without necessitating an entirely new set of dies for each change.

Another object of the invention is to provide a grille which may be readily varied in size in the field so that the heating contractor or other workmen, without special tools or fixtures may fit the grille to a given ventilator or heater opening, without having each separate size built in the factory.

My invention provides a grille construction for use with air conditioning units, with air and gas passages, automobile radiators, ventilators, heating units, etc., which is formed of stacked sheet

metal fin elements each with integral tubular projections whereby the individual elements may be stacked together, without other securing means to produce a strong and efficient grille, in which the elements are uniformly spaced and are free from rattling, whistling, etc.

Another object of my invention is to provide a more simply constructed and less expensive grille for air conditioning, radiator cabinets or automobile fronts the size of which is readily variable to suit special conditions and which is easily formed into decorative shape and will satisfactorily hide the radiator construction but will not materially reduce the rate of air flow through the opening.

Further objects and advantages of the invention will appear from the following description thereof taken in connection with the attached drawings which illustrate a preferred form of embodiment of my invention and in which;

Figure 1 is a front elevation of a grille for the front of an automobile radiator,

Figure 2 is a plan view with parts in section,

Figure 3 is a detailed side elevation with parts in section of one form of grille having curved portions on one face and V shaped notches on the other face of the grille elements,

Figures 4 and 5 are vertical sections taken substantially on the lines 4—4 and 5—5 of Figure 3,

Figure 6 is a side elevation with parts in section of a modified shape of grille,

Figure 7 is a plan view with parts in section, of the form of grille element shown in Figure 6 having reverse curve sections from front to back of the grille,

Figure 8 is a vertical section taken substantially on the line 8—8 of Figure 6,

Figure 9 is a side elevation partly in section of a further modified shape of grille element,

Figure 10 is a plan view also partly in section of the embodiment of Figure 9 in which the front and rear edges of the grille element are curved, the front of the elements being curved in a direction opposite to the curve of the rear edges,

Figure 11 is a vertical section taken substantially on the line 11—11 of Figure 9,

Figure 12 is a front elevation, and Figure 13 is a plan view of a construction similar to that shown in Figure 9 with the curvature of the edges of the grille being reversed for alternate elements at each side of the tubular projections,

Figure 14 is a side elevation, and Figure 15 is a plan view of a still further modified form of construction in which a series of deflections are

formed in the grille element between supporting units.

Figure 16 is a vertical section taken substantially on the line 16—16 of Figure 14.

5 Figure 17 is a partial plan view and Figure 18 is a section through a modified form of straight lip reinforced grille.

10 Figure 19 is a side elevation with parts in section of a drawing press and forming unit for forming the grille element.

Figure 20 is a side elevation partly in section showing a typical construction of the die block.

15 Grilles are commonly used in ventilators, air passages, radiator enclosures, etc., for decorative purposes or for deflecting the air in some manner or for generally covering the aperture or for all of these reasons. Such grilles have recently been mounted in front of the usual automobile radiator giving such vehicle an improved appearance. These grilles should be easy to construct, yet strong and adaptable to many uses. Economy in production and ability to vary design and shape without undue increase in cost is also an important feature. The grille and method of producing the same described herein ideally meets these conditions.

30 An illustrative form of grille 10 is shown as applied to the shell 11 of an automobile radiator covers the usual heat transferring element (not shown) and ornaments the appearance of the vehicle without materially reducing the rate of heat transfer. Such a grille, according to my invention may be built up of a plurality of elements 12 shown in Figure 3, each consisting of a fin member 14 which can be easily formed from a simple flat sheet or ribbon of metal such as copper, brass or steel. Each of the elements 12 has a partially flat sheet metal fin part 14, from which a series of tubular projections 14b have 35 been stamped or drawn and in which deflecting curves such as 15 and 16 may be formed. The projections 14b are formed from the same metal as the fin part 14 and they are slightly tapered so as to nest together when the fin parts 14 are 40 assembled into a grille.

45 A series of fins 14 having integral tubular projections 14b can readily be made by suitable drawing operations as hereinafter described in a continuous manner from a long strip or ribbon 50 of a metal. When these fin elements are cut to a suitable length corresponding to the length or width of the grille, the elements are stacked and pressed together with the tubular projections 14b telescoping partially in the tubular projections of 55 the next adjacent element to produce the desired height and the grille is complete without the insertion of rods or other securing means.

60 The conical shape of the projections 14b not only hold the elements together but act as a proper spacer to keep the elements uniformly spaced from each other, as well as to rigidly hold the entire stack or core together to prevent rattling or vibration etc. Again referring to Figure 3, the sectional portion shows the projections 65 14b of one fin element extending into the opening of the projection 14b of the adjacent element, thus securing without soldering, bolting or the like. The entire grille thus becomes practically one piece of metal without loose parts to rattle or vibrate.

70 This type of grille if applied in front of an automotive radiator will effectively hide the radiator itself and will control the air flow if desired. The grille elements may be placed sufficiently close together to make direct observa-

tion of the radiator impossible at a short distance or they may be readily spaced as desired.

Where a grille is used to control the air or gas flow through a given opening this is also accomplished particularly well by my form of grille as the fin portion 14 may be easily bent or formed to any shape or angle in the forming operation before they are assembled together. The deflecting portions 15 and 16 illustrate one form of ornamenting and deflecting curves, and 10 the rows of tubular projections 14b effectively divide the gas stream passing through the grille, and give stability or rigidity to the fin elements between the curved portions.

15 In Figures 2, 3 and 4, I have illustrated a gradual down curved shape 15 on the front edge of the strips between each of the rows of tubular projections 14b and at the same time, the rear edge of the elements are bent upwardly at a sharp angle into a notch 16, so that the front 20 of the element at 12 picks up the air stream and the notches 16 deflect the air in various directions against the radiator if this grille is used on an automobile. The angularity of these notches 16 may be used to curve the grille along 25 the length of the elements as is more clearly shown in Figure 2. By such means it will be seen that the grilles may be adapted to curved as well as flat surfaces as the curved front 18 illustrates.

30 The air or gas passing through this grille will 35 be forced upwardly as it passes rearwardly as is evident from the sectional constructions shown in Figures 4 and 5. All of the strips or elements are effective for this purpose and the rows of tubular projections bring about a further diversion 40 of the gases passing through. The relative depth of the curved portion 15 and the angularity of the notch portion 16 may be varied as desired.

45 Grilles of this type may be made of any desired width or height by merely varying the length 50 of the fin strips or the number stacked together. The elements 14 with the curved edges 15 and 16 and the integral projections 14b may be produced continuously and cut to any desired length in the machine hereafter described and when cut 55 and nested each element secures itself to the adjacent element due to the large number of telescoped tubular joints, the resultant core is of great strength regardless of the total number of elements.

60 The adaptability of my grille to other shapes is shown in Figures 6 to 16 which represent different forms of fin elements for directing the air or gases passing through the grille in different directions. The form of construction shown in Figures 6, 7 and 8 includes the fin element 20 curved downwardly at 21 on one edge and upwardly on the other edge 22. In such a case, the air passing through is not mixed and the percentage of free open space is very high. Good covering of any 65 radiator or other element to be concealed behind the grille, or the closure of an opening from sight is possible however, and the air may be forced in and up from one side or down and out through the other. Furthermore, the air or gas passing 70 through will not come out in jets as the multiplicity of small fin elements does not materially reduce the flow of air.

75 Another type of grille element is shown in Figures 9, 10 and 11 and although this construction 70 is somewhat similar to the construction of Figures 6, 7 and 8, it will be noted that it has a somewhat greater free opening. The deflecting vanes 25 are symmetrically curved downwardly in front and upwardly at 27 in the rear between the tele- 75

scoped joints formed by the tubular projections 26 which are spaced at regular distances across the face of the grille. The rearmost edges 27 of the fin elements are preferably oppositely curved 5 with respect to the foremost edges 25. The angularity is relative however, for the grille may have either face forward as desired and in one case the air will be forced upwardly whereas in the other case, it will be forced downwardly. A rod 28 may 10 be used in this and other forms to retain the grille elements together. This will additionally reinforce the elements and it may be soldered or welded or secured to the elements by suitable nuts and screw threaded ends.

15 The modification shown in Figures 12 and 13 is a variation of the form shown in Figures 9, 10 and 11. As will be particularly noted, the grille includes several unit sections 30, 31 and 32 each 20 of which is separated by the telescoped tubular projections 33. In two of the unit sections, 30 and 32 the fin or deflector element is curved upwardly as shown at 34 while in the central unit 31, the same fin is curved downwardly on the same edge as at 35. It will be noted, that the curvature 25 is the reverse on the rearward edge as two of the units have downwardly curved edges and the central unit has an upwardly curved edge 36.

In this form the air is slightly mixed due to the 30 vanes being alternated in such a way that the air flow is downward in one section and upward through the adjacent section thereby causing some intermingling or mixing.

The construction shown in Figures 14, 15 and 35 16 has a series of ruffled edges or flutes 40 on the edges of the fin element 41, the flutes on the front edge 41a being reversed with respect to the rear edge 41b. In cross section as shown Figure 16, it will be noted that the path is such that the air will be forced to divide into up and down currents 40 as it passes through the grille. The air will thus be very thoroughly mixed and will be deflected in all directions.

This construction may be readily varied so that 45 the vanes between each tubular projection are different so that the streams of air are blown down at the center vane between two projections and up at the center vane between the two projections immediately adjacent. It is readily possible to combine any groups of units as desired 50 and the fin edges may be bent into many irregular paths as desired to produce either ornamental deflections or mixing vanes.

The constructions shown and particularly the 55 last form are especially suited for use in air conditioning units where a quantity of untreated air is mixed with heated or cooled air already in the room to bring about the desired mixture for room purposes. Often the amount of cooled or heated air is but a small percentage of the entire mixture 60 and an intimate mix is necessary. As the air is passed through a grille of the type of Figures 14, 15 and 16 it will be clear that an intimate mixture will result.

A different form of grille element without the 65 shielding effect, is shown in Figures 17 and 18. This grille element 44 is similarly provided with drawn tubular projections 45 which telescope in the adjacent projections of the next elements. This form of grille element may preferably be 70 provided with projections 46 which may be of diamond or other shape which strengthen the element. A grille made of such elements will be simple and sturdy in construction and will be particularly adapted to certain particular uses 75 where concealment is not essential.

The open area of these forms of grilles is a high percentage of the gross frontal area or size of opening for the fin elements can be of relatively thin construction and separate securing means are unnecessary due to the automatic securing of the joints by the telescoped relation of the tapered projections. Soldering can be used with no difficulty but it usually is found unnecessary. No rattling or whistling occurs due to the tight fit of the projections nesting into each other. An unusual advantage of my grille and method of constructing the same is that all these various forms as well as various sizes may be produced without necessity for a complete separate die for each form produced. 15

In Figures 19 and 20, I have illustrated a form of machine and die suitable for carrying out my method of forming the grilles I have described. It is of the type generally known as a forming and punching machine using female die member 20 50 preferably carried on a base plate or bed 51 supported by the frame 52 and the upper or male die plate 53 carried on the end of platen 54 which is guided in a suitable manner and reciprocated through suitable power means, (not 25 shown) and fly-wheel 55.

The grille elements 14, 21, 25 etc., are formed from a strip of suitable material such as copper, brass, aluminum, steel, etc., which is presented in Figure 19 by the character 56 and shown in a 30 coil or spool 58. The flat strip or ribbon of metal 56 is moved progressively through the dies 50 and 53 by the feed rolls 72. A tensioning roll 59a may be used to regulate the delivery of the strip and take out the slack. An oil bath 59 is also 35 preferably provided for the strip before it enters between the dies.

The preferred formation of the dies is shown in Figure 20. A plurality of forming tools 60, 61 for gradually drawing the projections from the 40 strip and a perforating tool 62 are carried in the male die 53 and below these tools are female depressions 61a, etc., to assist in forming the projections. Spring pressed plunger 63 which force the strip out of the female depressions are provided 45 in each depression. A separate die block 65 is mounted near the end of the die 50 for curving the front and rear of the strips on the edges as shown at 15, 16, 25, 27, etc., in the previous figures. The die block has a cooperating plunger 50 66 to give the desired curvature to the fin edges. Preferably, the die 66 and the die block 65 are 55 separately mounted in the dies 50 and 53 so that they can be removed and changed if a differently curved element is desired.

The strip 56 is fed progressively through the machine as is well known in the art, the partly formed projections moving from one die depression to the next until formed to the desired depth. Stop means are provided to stop the strip in proper registry with each die depression while the rolls 72 move the strip one step forward when the die 53 is elevated.

A stacking machine 70 is preferably mounted 65 near the press and the strips 14 are fed of the proper length into the stacking machine by feed rollers 72 whereupon the cutter 71 operates to cut strips of the desired length. The stacking machine has a synchronously driven screw 73 moving the stacking table 74 downward the 70 proper amount as each new element 14 is added. At a suitable time, the table 74 can be moved upwardly to compress the elements with the projections 14b nesting together into a final completed grille. 75

It is of course to be understood that the method of drawing the tubular projections and bending the fin edges and the apparatus for stacking the elements is subject to variations and other apparatus 5 may be found suitable. The apparatus shown and described however, has been found to be satisfactory. The strips are drawn in step by step relation, each punch drawing the tubular projection the necessary additional amount until the projection is perforated when it is completely formed. The strips are then bent or deflected in the dies 65—66 to the desired angularity after which the fin elements are stacked into a core.

A more complete operation of this type of machine 15 will be found in my Patent No. 1,669,761.

While I have shown preferred forms of embodiment to which my invention is susceptible, I am aware that other modifications may be made therein and I therefore desire a broad interpretation of my invention within the scope and spirit 20 of the disclosure herein and of the claims appended hereinafter.

I claim:

1. A grille comprising a plurality of fin elements 25 having integral tubular projections extending therefrom, the tubular projections of adjacent elements being telescoped together, each of said elements cooperating with adjacent elements to form a rigid structure, said fin elements having portions bent out of the plane of the element in unperforated parallel surfaces to deflect 30 gases passing through said grille without substantial change in distance between fins.

2. A grille comprising a plurality of fin elements, said elements having tubular projections 35 extending therefrom, said tubular projections telescoping in adjacent projections, the fin elements being uniformly spaced by said projections and subdividing the gas stream passing through the grille, and a plurality of curved portions adjacent the edge of the fin elements to direct 40 the flow of gas.

3. In a fin and tube type grille, a plurality of telescoped tubular projections, a plurality of fins integral with said projections and dividing 45 the air which flows between said rows of projections into a plurality of streams, said fins having curved edges projecting from the spaces between said tubes, and curved edges being equally spaced from one another for deflecting the air 50 streams flowing therethrough without substantially varying the cross-sectional area of the passages between the fins.

4. A grille of the class described comprising 55 an integral stack of separate fin and tube type elements, the fin elements having integral tubes telescoping adjacent fin tubes and being deformed on their edges in parallel relationship to bring about an intermixing of air passing 60 therethrough, the thickness of the fin elements

and the relative spacing thereof being such as to not materially reduce the volume of air flowing therethrough with respect to the gross frontal area.

5. A grille for air conditioning units comprising 5 a series of stacked fin and tube type metallic elements, each of said elements having a single row of relatively long and narrow integral tubular projections, the tubular projections of the respective elements being partially telescoped and secured in the tubular projections of adjacent elements, and the fins being deformed in parallel relationship and in gradual curves to deflect and mix gases passing through said grille.

6. A grille for mixing gases passing there- 15 through which comprises a series of fin elements having integral tubular projections thereon, said elements being stacked with the tubular projections of one element extending into the tubular 20 projections of an adjacent element, said tubular projections forming rows of joints securing the grille, said fin elements having curved parallel edges on one face and notched edges on the other face between the rows of tubular 25 projections.

7. A grille for mixing gases passing there- 30 through which comprises a series of fin elements having integral tubular projections thereon, said elements being stacked with the tubular projections of one element extending into the tubular 35 projections of an adjacent element, said tubular projections forming rows of joints securing the grille, said fin elements having curved parallel edges on one face and oppositely curved 40 parallel edges on the opposite face.

8. A grille for mixing gases passing there- 45 through which comprises a series of fin elements having tubular projections thereon, said elements being stacked with the tubular projections of one element extending into the tubular projections of an adjacent element, said tubular 50 projections forming rows of joints securing the grille, said fin elements having curved parallel edges on one face between rows of tubular projections, the alternate rows of curved edges being oppositely disposed to the other rows of curved edges on the same face.

9. A grille for mixing gases passing there- 55 through which comprises a series of fin elements having a single row of tubular projections thereon, said elements being stacked with the tubular projections of one element extending into the tubular projections of an adjacent element, said tubular 60 projections forming rows of joints securing the grille, the edges of said elements having a plurality of curves on one face between each row of tubular projections, the edges on the other face being oppositely curved.

JOHN KARMAZIN. 60
